ELECTRIC WATER HEATER

Filed Aug. 26, 1924

5 Inventor
SAMUEL D. NESMITH

By A. B. Bowman

Attorney

UNITED STATES PATENT OFFICE.

SAMUEL D. NESMITH, OF SAN DIEGO, CALIFORNIA, ASSIGNOR OF PART INTEREST TO A. S. BRIDGES, J. B. OSBORN, MRS. KATHRYN OSBORN, J. H. BULMER, AND MRS. MARY E. NESMITH, ALL OF SAN DIEGO, CALIFORNIA; ROGER WELLES AND R. R. RICHARDSON, BOTH OF THE UNITED STATES NAVY; E. J. CALLAHAN, OF GUADALAJARA, MEXICO; GEORGE H. SCHMIDT, WALTER C. STITT, F. F. GRANT, H. M. SAMMIS, PAUL J. HARTLEY, AND R. C. EASOM.

ELECTRIC WATER HEATER.

Application filed August 26, 1924. Serial No. 734,254.

My invention relates to electric water heaters, and the objects of my invention are: first, to provide an electric heater of this class having a plurality of flat, vertically positioned, water conducting channels positioned side by side and parallel to each other, and which are heated by means of electric heating elements positioned contiguous to and between the adjacent water conducting channels and insulated therefrom, the heater being provided with water conductors communicating with the lower and upper ends of all of the water conducting channels thereof, whereby a large volume of water will pass through the channels with a minimum amount of resistance and be quickly heated therein; second, to provide a water heater of this class which is provided at its upper and lower ends with water passages increasing in cross-section from the one side to the opposite side to which the respective inlet and discharge conductors are connected, which passages communicate with the upper and lower ends of the water conducting channels, thus reducing to a minimum the resistance of the water passing therethrough and providing means to permit a large, continuous, substantially uninterrupted flow of water through the heater; third, to provide tubes for a heater of this class, the thickness of the walls of which is such as to uniformly conduct the desired amount of heat to the interior of the water channels; fourth, to provide a substantially instantaneous and efficient electric water heater of proportionately large volume; fifth, to provide a novelly constructed water heater of this class, and sixth, to provide an electric water heater which is simple and economical of construction, durable, and which will not readily deteriorate or get out of order.

With these and other objects in view, as will appear hereinafter, my invention consists of certain novel and practical features of construction, combination and arrangement of parts and portions, as will be hereinafter described in detail and particularly set forth in the appended claims, reference being had to the accompanying drawings and to the characters of reference thereon,

which form a part of this application, in which:

Figure 1 is a front elevational view of my electric water heater, with the front wall of the casing and certain other parts and portions broken away and in section to facilitate the illustration; Fig. 2 is a sectional elevational view thereof, with the section taken through 2—2 of Fig. 1, and Fig. 3 is a front elevational view thereof, with a portion of the front wall of the casing broken away and in section.

Like characters of reference refer to similar parts and portions throughout the several views of the drawings.

The water tube supporting members 1 and 2, end wall members 3, water tubes 4, end water passage members 5 and 6, bolts 7, inlet conductor 8, discharge conductor 9, cores 10, electric heating elements 11, insulating material 12, terminal posts 13, electric insulating plates 14, terminal connecting members 15, nuts 16, electric conductors 17 and 18, heat insulating material 19, and the heater casing 20, constitute the principal parts and portions of my water heater structure.

The water tube supporting members 1 and 2 of my water heater are identical in construction, but positioned in reverse order in horizontal positions, and are supported in spaced relation with each other at their ends by means of the end wall members 3. Extending vertically between the members 1 and 2 are the water tubes 4, which extend through said members and are welded or riveted over at their projecting ends. These water tubes 4 are preferably made of flattened copper tubing of large diameter, or of other material of high heat conductivity, so that a substantially thin channel for the passage of water is formed therethrough. Against the upper face of the tube supporting member 1 and the bottom face of the tube supporting member 2 are positioned, respectively, the water passage members 6 and 5, which are secured to the members 1 and 2 by means of bolts 7, the bolts 7 at the ends of the members 5 and 6 serving also to secure the members 1 and 2 to the end wall members 3, as shown in the

drawings. The members 5 and 6 are provided with large chambers or passages 5^a and 6^a, which communicate directly with the lower and upper ends of the water tubes 4. 5 The one end of the passage member 5 is provided with a large inlet conductor 8, and the one end of the water passage member 6 is provided with a large discharge conductor 9. The width of each of the members 5 and 6 is substantially the same as the width of the water tube. The cross-sectional area of the passages 5^a and 6^a of the members 5 and 6, respectively, at the ends thereof connected with the conductors 8 and 9, is 10 substantially equal to the cross-sectional area of all the water tubes combined, the depth of the passages decreasing gradually toward the opposite ends of the members 5 and 6, so that the cross-sectional area at any place within the passages is 15 substantially equal to the sum of the cross-sectional areas of the water tubes on the opposite side of the plane, where the cross-section is taken, from the conductor connected with the particular passage. Thus, the resistance of the water flowing through the end passages and the tubes is 20 reduced to a minimum. To provide a gradually decreasing passage in the end members 5 and 6, as described, the outer or bottom and top walls of the members 5 and 6 are of necessity inclined with the horizontal plane. To provide a rectangular construction for the heater, I have 25 provided ribs 5^b and 6^b on the outer sides of the inclined walls, one at the front and back edges thereof and one at its middle portion, so that the heater assumes a rectangular shape, as shown best in Figs. 1 and 30 2. The members 5 and 6, it will be noted, are of identical construction but positioned in reverse order relatively to each other. Between the side water tubes 4 and the end wall members 3 is provided heat insulating 35 material 19, as shown best in Fig. 1.

It will be seen, therefore, that I provide headers at each end of the heater to which the water tubes are individually or independently secured, these headers providing 40 water passages of gradually varying capacity, the water passage in the header at one end of the tubes gradually and uniformly increasing in capacity while the header at the opposite end of the heater uniformly 45 and gradually decreases in capacity in the same direction. This provides a construction whereby the formation of air pockets or steam pockets in the headers will be eliminated while at the same time the minimum resistance is offered to the flow of water 50 through the heater.

Each electric heating unit of my water heater consists of electric heating elements 55 wound around a core 10 of electric insulating material and molded in a casing 12

of heat conducting and electric insulating material, preferably alundum. At the ends of the heating elements 11 are provided outwardly extending terminal posts 13, which extend through the molded casings 12 and an electric insulating plate 14, one of which is positioned at the front and another at the back side of the heater. The terminal posts 13 of each unit are connected with the corresponding post of the adjacent and separately positioned heating elements by means of the connecting members 15 and the nuts 16.

The water heater is preferably enclosed by means of a sectional casing 20 consisting of the front casing member 20^a, covering preferably the front, top and side walls of the heater, and the rear casing member 20^b, covering the back side of the heater. Between the end passage members 5 and 6 and the sides of the heater, and the enclosing casing 20, is preferably positioned a heat insulating material 19 to confine the heat within the heater.

It is obvious from this construction, as illustrated in the drawings and disclosed in the foregoing specification, that there is provided an electric water heater as set forth in the objects of the invention and throughout the specification, and though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an electric water heater, the combination of two headers, one at the top and one at the bottom of the heater, a plurality of vertically extending, spaced apart, flattened water tubes extending from one header to the other and communicating with the interiors thereof to connect said tubes in multiple through said headers, electrically-insulating heat-conducting material providing electrical heating elements interposed between each pair of adjacent water tubes, end plates at the ends of said headers adjacent the end tubes, said end plates being bolted to the headers, heat-insulating material interposed between said end plates and the adjacent tubes, electrically-insulating side plates provided at each side of said heater, a casing for said heater and heat-insulating means interposed between said casing and said heater.

2. In an electric water heater, the combination of two headers, each of which is of gradually and uniformly varying cross section, end or spacer plates bolted to said

headers and connecting said headers to each other, a plurality of flattened, vertically-extending water tubes extending from header to header and communicating therewith, said tubes being independently secured to said headers and arranged in spaced relation to each other, electrical heating elements, independently removable, mounted between and adjacent each pair of water tubes and electrically insulated from the tubes, removable electrically-insulating plates ex-

tending along the sides of the heater and through which are passed the leads or conductors for the heating units, an outer casing for said heater and heat-insulating material interposed between said outer casing and said end plates, headers and side insulating plates. 15

In testimony whereof, I have hereunto set my hand at San Diego, California, this 2nd 20 day of August, 1924.

SAMUEL D. NESMITH.
